CONTROL DEVICE FOR MACHINES

Alonzo K. Marsh, Summit, N. J., assignor to
A. Kimball Company, New York, N. Y., a cor-
poration of New York

Application April 4, 1935, Serial No. 14,574

6 Claims. (Cl. 192—131)

This invention relates to control devices for machines and particularly to safety devices adapted to protect the machine operator from injury.

5 In recent years there has been an increasing demand for safety devices in connection with machines such as cutting machines, punch presses and the like, and in some states laws have been enacted requiring that certain safeguards be provided. For example, it is sometimes required 10 that the operating controls of the machine be such that the operator is required to use both hands to start the machine, the theory being that if both hands are so employed, it is unlikely that either hand will be in a dangerous 15 position. Also it is sometimes required that the controls be such that the machine will be non-repeating, that is, it will of necessity be stopped at the end of each operating cycle and must be 20 started again by the operator.

It is an object of the present invention to provide a safety control device of very simple, inexpensive construction which will meet these and other requirements.

25 Other objects and advantages of the invention will appear hereinafter.

A preferred embodiment of the invention selected for purposes of illustration is shown in the accompanying drawings, in which,

30 Figure 1 is a top plan view.

Figure 2 is a front elevation.

Figure 3 is a composite end elevation and sectional view of the left side of the machine.

35 Figure 4 is a fragmentary end elevation of the right side of the machine, and

Figure 5 is a sectional view of the locking pin.

Referring to the drawings, the control device has been illustrated as applied to a cutting machine, but inasmuch as the operation of the cutting knife forms no part of the present invention, the operating mechanism is not illustrated, although the cutting knife 1 is indicated semi-diagrammatically in Figures 1, 2 and 3 in order to indicate its position relative to the control devices. It will be understood that the said operating mechanism includes a conventional clutch.

The control devices forming the subject matter 50 of this invention comprises a clutch operating lever which, in accordance with the present invention, comprises two parts 2 and 3, which parts are pivotally connected by the bolt 4 so that the part 3, which for convenience may be called the clutch handle, is relatively movable with respect 55 to the part 2 which may be called the clutch

lever, the said clutch lever 2 being connected to the usual clutch (not shown) through any suitable connections (not shown).

Means are provided for locking the parts 2 and 3 together in order that they may operate as a unit to control the clutch, and the said means may comprise a pin 5 mounted in an aperture 6 in the clutch handle, and which may be depressed to cause the end of the pin 5 to enter the aperture 7 in the lever 2. The pin is normally held out of the aperture 7 by the coil spring 8 which is interposed between the clutch handle 3 and the head 9 of the pin.

Means are provided for operating the pin 5 comprising a lever 11 mounted on a shaft 12 carrying a cam plate 13 located above the pin 5 and normally in engagement with the head 9 of the pin. As will be observed, the clutch handle 3 and the lever 11 are located at opposite ends of the work-table 14 at positions separated far enough so that it is impossible for the operator to operate both levers with one hand.

It will also be observed that it is necessary for the operator to move both levers in order to move the clutch lever 2 to start the machine. Thus, 25 since the pin 5 is normally out of engagement with the lever 2, movement of the clutch handle 3 will have no effect, since the handle 3 will merely swing about its pivot 4. In order to operate the machine, therefore, the operator must 30 first move the handle 3 to bring the apertures 6 and 7 into register, and then move the lever 11 to cause the cam plate 13 to depress the pin 5. When the pin 5 has entered the aperture, the clutch lever 2 may be moved to the operating 35 position by moving the clutch handle 3. If either the clutch handle 3 or the lever 11 is released by the operator at any time, the machine will be stopped immediately, for if the handle 3 is released, the lever 2 is restored to normal non-operating position by the spring 15 which connects the lever 2 to a fixed part of the machine such as the leg 16, thus disengaging the clutch and stopping the machine. If the clutch of the machine is supplied with a spring tending to disengage the same, the spring 15 may be dispensed with, or if desired, the spring 15 may be used to supplement the usual clutch spring. On the other hand, if the lever 11 is released while the machine is in operation, the spring 8 lifts the 50 pin 5 out of aperture 7, thus disengaging the handle 3 from the lever 2 and permitting the lever 2 to return to normal position under the influence of the spring 15 or the clutch spring, thus stopping the machine. It will be observed 55

40

45

50

55

that the cam plate 13 is of sufficient area to engage the pin 5 during the entire movement of the lever 2 and handle 3 from their normal non-operating positions as illustrated in Figures 1 and 5 2 to their operating or clutch engaging positions somewhat to the left.

Means may also be provided for automatically causing a disengagement of the clutch at the end of each operating cycle of the machine. 10 Such means may comprise a bell crank 16 pivotally mounted on the support 17 and having an arm 18 which engages a trip cam 19 mounted on the operating shaft 20 of the machine. The other arm 21 is arranged to engage the under side of 15 the lever 22 on the shaft 12, the arrangement being such that at the end of each operating cycle the trip cam 19 will operate the bell crank to cause the shaft 12 to be moved to lift the cam plate 13 thus permitting the pin 5 to move out 20 of the aperture 7, thus causing the machine to stop.

It will be understood that the invention may be variously modified and embodied within the scope of the subjoined claims.

25 I claim as my invention:

1. A safety control device comprising an operating lever comprising two pivotally connected parts, one of said parts being adapted for operative connection to a clutch of the machine to be controlled, resilient means tending to hold said part normally in non-operating position, a pin mounted on one of said parts, said other part being provided with an aperture adapted to receive said pin so as to lock the parts together, resilient means normally tending to hold said pin out of said aperture, a second operating lever, a cam operated by said second lever for operating said pin to push the same into said aperture and holding the same therein while said 30 first operating lever is moved to operating position.

2. A safety control device comprising an operating lever comprising two connected relatively movable parts, a second operating lever, means 35 including a pin mounted on one of said parts

and a cam operated by said second operating lever for operating said pin to prevent movement between said relatively movable parts while permitting them to move together to control the operation of a machine.

5

3. A safety control device comprising an operating lever comprising two connected relatively movable parts, a second operating lever, means operated by said second operating lever for preventing movement between said relatively movable parts, while permitting them to move together to control the operation of a machine, resilient means for releasing said means, and resilient means for holding said first operating lever normally in non-operating position.

15

4. A safety control device comprising an operating lever comprising two connected relatively movable parts, a second operating lever, and means operated by said second operating lever for preventing movement between said relatively movable parts, while permitting them to move together to control the operation of a machine.

20

5. A safety control device comprising an operating lever comprising two connected relatively movable parts, a second operating lever, means operated by said second operating lever for preventing movement between said relatively movable parts, while permitting them to move together to control the operation of a machine, and means operated by the machine for operating 30 said second operating lever to release said relatively movable parts upon completion of one operating cycle of the machine.

25

6. A safety control device comprising an operating lever comprising two connected relatively movable parts, a second operating lever, means including a pin mounted on one of said parts and a cam operated by said second operating lever for operating said pin to prevent movement between said relatively movable parts while permitting them to move together to control the operation of a machine, and means operated by the machine for releasing said pin upon completion of one operating cycle of the machine.
